UNITED STATES PATENT OFFICE

2,520,625

STORM VENTILATOR

William Frederick Dean, Warrington, Fla.

Application June 27, 1946, Serial No. 679,828

3 Claims. (Cl. 160—57)

1

My present invention relates to an improved window ventilator and more particularly to the type of ventilator adapted to be mounted exteriorly of the conventional window frame so that the wind driven rain will not penetrate the window even though the upper sash may be open. My ventilator also provides for the raising of the ventilator covering to permit the access of air and breezes during fair weather.

In the accompanying drawings I have illustrated one complete example of the physical embodiment of my invention according to the best mode I have thus far devised but it will be understood that various changes and alterations may be made in the exemplified structure within the scope of the appended claims.

In the drawings:

Figure 1 is a skeleton view in perspective of the ventilator frame without the covering.

Figure 2 is an elevational view of the cover for the frame.

Figure 3 is a perspective view of the cover roller.

Figure 4 is a perspective view of the handle for the roller crank.

Figure 5 is a partial side elevational view of the side frame.

Figure 6 is a perspective view of the ventilator with the side covers and the rolling cover in extended position.

Referring now to the drawings wherein like characters indicate like parts, I have illustrated the ventilator of my invention embodying the side frame members 2 and 4, with the vertical frame members 6 and 8 secured by means of the screws 9 to the conventional window frame 10. These frame members are preferably made of angle iron as shown although other materials and shapes may be well employed.

The free ends of the side and vertical members are connected and secured in position by the arcuate supports 12 and 14 of the same material, said arcuate supports having inwardly extending flanges 14' and the transverse braces 15 properly space the supports.

Snap buttons 16 are provided along the exterior of the various members and supports to secure the side coverings in position, and slots 18 are fashioned in the cross frame 5 between the joined ends of the arcuate supports and the side frames 2 and 4.

A cover plate 20 preferably of metal and having side portions 22 depending therefrom covers the upper portion of the ventilator and provides protection from the elements of the operating mechanism of the roller 24 having a stub shaft

2

25 journaled in the arcuate support on one side and formed with spaced lugs 26, and journaled on the other arcuate support by means of the crank 28 having an aperture in the end thereof as at 29.

The depending portions 22 of the cover have forwardly extending ends fitted into and secured to the arcuate supports 12 and 14 respectively. The brace elements 15 for the frame are connected between the forwardly extending ends of the depending portions 22 as indicated at 45. The braces in this manner will not interfere with the operation of the retractile cover 34 and yet give to the brace members adequate connection to serve their purpose.

A separate handle 30 is shown having a nose 31 for engagement with the aperture of the crank in order that the crank may be operated to rotate the roller from a person inside the room.

20 The above frame is covered on the sides by the side pieces 32 formed with rows of spaced co-acting snaps 33 for the buttons 16, and a retractile cover 34 of waterproof canvas is fashioned with edges reinforced by metal strips 36 and hooks 38 on the outer edge for engagement with the slots 18, and slots 40 are provided along the upper edge for engagement with the lugs 26 of the roller 24.

25 A plate 42 covers an opening 44 in the side piece 22 for removal of the roller if necessary, and in operation the retractile cover is secured to the roller by attaching the slots on the lugs and the cover is then stretched out and the hooks 38 engage with the slots 18. The metal strips along the sides of the canvas cover will ride on the angle frames and will prevent sagging of the cover. In fair weather or whenever so desired, the cover may be raised by unhooking the hooks from the slots 18 and rotating the roller through the crank by means of the handle 30.

30 From the above description of the construction and operation of the ventilator of my invention it will be apparent that the device will afford an ornamental and useful addition to any window structure and will afford a safe means of preventing the entrance of rain while still permitting the circulation of air with the upper sash of the window in lowered position.

The ventilator of my invention described above 35 will offer a more advantageous use than the conventional type because the entire structure need not be removed when the ventilator is deemed unnecessary and the canvas coverings on the side and the roll cover may be readily removed. Furthermore if additional ventilation over that pro-

vided is desired, the side coverings may be removed and reattached with facility when desired thus presenting a readily adjustable and convertible window ventilator to meet the various weather requirements.

Having thus fully described my invention what I claim as new and desire to secure by Letters Patent is:

1. A window ventilator comprising vertical frame members adapted to be secured to the opposite sides of a conventional window frame and having fastener elements thereon, side frame members extending outwardly from the lower ends of said vertically extending members and having fastener elements thereon, arcuate supports extending respectively from the upper ends of the vertically extending frame members to the outer end of the side frame members, said arcuate supports having inwardly extending flanges and fastener elements, canvas side pieces connected to the frame members and arcuate supports and having fastener elements cooperating with the fastener elements thereof, a top cover plate extending between the arcuate sections at the upper ends thereof and having depending side portions connected to the arcuate support and to the vertically extending frame members, a transversely extending brace extending between the lower ends of the arcuate supports and of the side frame members, a roller connected between the side portions of said cover plate and having an operating handle thereon, a retractile cover having end strips, the sides of said cover extending over the flanges of the arcuate supports and supported by the same when the retractile cover has been ex-

5

tended, cooperating fastener means on the opposite ends of the cover, the roller and the transversely extending brace at the outer ends of the arcuate support releasably retaining the retractile cover on the support, the cover upon being released at its lower edge from the transverse brace being adjustable over the flanges by the roller to provide an opening in the front of the ventilator and between the arcuate supports.

2. A window ventilator as defined in claim 1 and fastener elements on the depending portion of the cover for receiving cooperating fastener elements of the side pieces.

3. A window ventilator as defined in claim 1, and transverse braces extending between the depending portions of the top cover, said depending portions of the top cover extending forwardly of its upper edge and secured into the arcuate supports, the braces being secured to the forwardly extending ends of the depending portions.

WILLIAM FREDERICK DEAN.
